United States Patent Office

Des. 183,174
Patented July 8, 1958

183,174

MOBILE SERVICE STATION

Georges Jacques Miron, Montreal, Quebec, Canada

Application March 18, 1957, Serial No. 45,305

Term of patent 14 years

(Cl. D14—3)

FIG.1

FIG.2

Figure 1 is a top plan of a mobile service station, embodying my new design. Figure 2 is a side elevation thereof.

The essential features of my design reside in those portions shown in full lines.

I claim:

The ornamental design for a mobile service station, as shown and described.
